PAUL CRICCHIO, OF NEW YORK, N. Y., ASSIGNOR TO MAJESTIC LAMP WORKS, OF NEW YORK, N. Y., A PARTNERSHIP OF PHILIP SILBERHARTZ, JACOB SILBERHARTZ, AND HARRY SCHEINER, ALL OF BROOKLYN, NEW YORK

DESIGN FOR A PLATE FOR SMOKERS' SETS

Application filed August 2, 1929. Serial No. 32,286. Term of patent 3½ years.

To all whom it may concern:

Be it known that I, PAUL CRICCHIO, a citizen of the United States, and a resident of New York, county of Bronx, and State of New York, have invented a new, original, and ornamental Design for a Plate for Smokers' Sets, of which the following is a specification, reference being had to the drawing, forming a part thereof.

The single figure of the drawing shows a perspective view of the plate for smokers' sets.

I claim:

The ornamental design for a plate for smokers' sets substantially as shown.

PAUL CRICCHIO.
